CAR AXLE JOURNAL LUBRICATOR

Karl A. Klingler, 111 S. Wright, Naperville, Ill.
Filed July 3, 1959, Ser. No. 824,864
15 Claims. (Cl. 308—91)

My invention relates to improvements in railroad car journal lubricators and has for one object to provide a light, flexible reliable railroad car axle journal lubricator which will pick up free oil from an oil reservoir in the bottom of the journal box and discharge it against the journal so that the journal may be lubricated by free oil without the need of waste, packing or the like.

Another object of the invention is to provide a journal lubricator which may be installed without any change or modification of the journal box.

Another object is to provide a lubricator which may be installed by unskilled labor whereby all the operator has to do is to hook the lubricator in.

Other objects will appear from time to time throughout the specification and claims.

My invention is illustrated more or less diagrammatically in the accompanying drawings, wherein—

FIGURE 1 is a side elevation of a part of the journal showing the lubricator in place in elevation and part section;

FIGURE 2 is a section through the journal showing the lubricator in place thereon;

FIGURE 3 is a detail section of a part of the journal showing the lubricator with parts in elevation and parts in section and parts omitted;

FIGURE 4 is a section along the line 4—4 of FIGURE 3 with the lubricator wheels in place;

FIGURE 5 is a plan view of a part of FIGURE 3.

Like parts are indicated by like characters throughout the specification and drawings.

The railroad car journal 1 is flanged at its end at 2 and is adapted to be associated with the usual bearing brass and wedge in a journal box, the details of which form no part of this invention, are conventional and in the interest of simplicity and clarity are not here illustrated.

The stirrups or wire loops 3 may be supported in any desired manner to hang down on both sides of the journal and support the lubricator which is the subject of the present invention. The lubricator includes the friction wheels 4 and 5 so mounted on inclined stub shafts 6 and 7 that they contact each other below the journal and each wheel separately contacts and is frictionally driven by the journal.

Segmental arcuate guide yokes 8 and 9 concentric with the journal have at their lower ends parallel, opposed, generally radial extensions 10 and 11, apertured to receive the ends of the fixed tie pin 12, tubular in the interest of reducing weight. The extensions 10 and 11 are inwardly flanged to support the sleeve 13 which in turn carries the elastomeric sleeve 14. Encircling the sleeve 14 are the concentric sleeves 15 and 16. Each sleeve at its inner end terminates in wedge shaped blocks 17 and 18, their extensions being in opposition to each other on opposite sides of the vertical plane of the axis of the pin 12 and so dimensioned as shown in FIGURE 4 as to permit relative limited angular movement toward and from each other. The rubber sleeve 14 is permanently attached to the sleeve 13 and is in frictional engagement with the sleeves 15 and 16. This permits the limited movement between the two sleeves necessary for angular displacement of the support blocks 17 and 18 during assembly. The rubber sleeve serves as a cushion to dampen out chatter and vibration and to prevent wear and distortion of the parts. The support blocks 17 and 18 carry the stub shafts 6 and 7.

2

The guide yokes 8 and 9 guide and position tension springs 19 and 20 which are anchored at their lower ends on the extensions 10 and 11 and are hooked at their upper ends on the stirrups 3, the yokes holding the springs 5 out of contact with the journal. Extending laterally in opposite directions from the guide yokes 8 and 9 are guide pads 21 and 22 parallel with the journal axis to hold the lubricator in general alignment and contact with the journal.

10 The friction wheels 4 and 5 each carries a soft flexible generally conical corrugated elastomeric lubricant distributing cup 23. The cups are corrugated for flexibility as they come into and out of contact with the journal and for added efficiency in throwing the oil from the 15 reservoir in the box. On their upper peripheries these cups engage the journal along an extended length thereof thereby economically conveying the oil to the journal, the oil being brought up from the oil reservoir because as they dip into the oil reservoir on their lower peripheries 20 they extend down substantially below the oil level.

The use and operation of the invention are as follows:

The lubricator is hung below the journal on the two stirrups supported in any desired manner on opposite sides of the journal. The two springs being under tension 25 and being held out of contact with the journal by the guides urge the two friction wheels into contact with the underside of the journal and tend to rotate their intersecting axes in such direction as to bring the two friction wheels into contact with one another and with the journal. 30 Thus there is a friction driving contact between each wheel and the journal and a friction driving contact between the two wheels so that the two wheels rotate in unison giving a double torque effect. FIGURE 4 shows how support blocks 17, 18 may rotate to permit relative 35 angular movement of the axes of the two wheels driving assembly the support blocks limiting such angular movement in opposite directions.

As the journal rotates driving the two friction wheels, the lubricator cups spin at relatively high speed, picking 40 up the oil from the well or reservoir, throw some of it outwardly diagonally, against the axle spraying the oil generally throughout the box though some of the oil is conveyed mechanically to and smeared upon the surface of the journal. This gives a wide distribution of the 45 lubricant. The frictional resistance to the movement of the lubricator is negligible and the lubricator can be put in place without any change, any modification of or addition to the journal box. The stirrups may be supported in any desired manner, the support forming no part of the 50 present invention is not illustrated but is illustrated in my co-pending application.

The guide pads which project laterally from the guide yokes are in light frictional contact with the journal and tend to maintain the lubricator support in proper alignment with the journal because they maintain parallelism with the journal axis, to prevent any contact of the wheels with the box wall thus safeguarding the wheels against damage.

This friction arrangement, in cooperation with the tension of the springs damps out tangential movement and maintains the lubricator wheels in permanent contact with the underside of the journal and maintains their axes generally in the vertical plane which includes the journal axis.

60 The diagonally axised arrangement of the two friction drive members 4 and 5 is such that the power applied to each of those two members or wheels where they contact the journal is transmitted in terms of torque at the other end of the diameter so that we get greatly increased double torque to insure the rotation of both of 65 the wheels.

This diagonal arrangement of the two wheels with the

flexible oil distributing cup is effective because where the oil distributing cup contacts the journal it extends horizontally away from the drive wheel and has a wide area in contact with the journal but where it extends downwardly into the oil well it has a wide vertical insertion. Thus the flexible cup extends far below the drive wheel but is so flexible that even if the journal box should come in contact with the flexible cup as it normally never does the cup would not be damaged.

The diagonal disposition of the axes of the two friction wheels and of the lubricating cup results in throwing the oil all over the axle at the same time lubricating the axle and cooling it in sharp contrast with the situation where oil is merely smeared on the journal at the point of contact between the journal and the lubricator.

I claim:

1. A lubricator for railroad car axle journals comprising two friction wheels mounted for rotation about inclined intersecting axes, means for supporting them below a car axle journal and biasing them upwardly against the journal for separate frictional contact therewith and with each other, the wheel supporting means comprising a pivot pin in a plane perpendicular to the axis of rotation of the journal, separate, concentric, aligned sleeves encircling and free to rotate through a limited angle about the pin and carrying at their ends opposed overlapping support blocks, bearing pins carried by the blocks on which the wheels are mounted.

2. A lubricator for railroad car axle journals comprising two friction wheels mounted for rotation about inclined intersecting axes, means for supporting them below a car axle journal and biasing them upwardly against the journal for separate frictional contact therewith and with each other, the wheel supporting means comprising a pivot pin in a plane perpendicular to the axis of rotation of the journal, separate, concentric, aligned sleeves encircling and free to rotate through a limited angle about the pin and carrying at their ends opposed overlapping support blocks, bearing pins carried by the blocks on which the wheels are mounted, an elastomeric sleeve interposed between the pin and the aligned sleeves and adhering thereto.

3. A lubricator for railroad car axle journals comprising two friction wheels mounted for rotation about inclined intersecting axes, means for supporting them below a car axle journal and biasing them upwardly against the journal for separate frictional contact therewith and with each other, the wheel supporting means comprising a pivot pin in a plane perpendicular to the axis of rotation of the journal, separate, concentric, aligned sleeves encircling and free to rotate through a limited angle about the pin and carrying at their ends opposed overlapping support blocks, bearing pins carried by the blocks on which the wheels are mounted, the wheels being mounted for rotation on axes located in the vertical plane of the axis of rotation of the journal.

4. A lubricator for railroad car axle journals comprising two friction wheels mounted for rotation about inclined intersecting axes, means for supporting them below a car axle journal and biasing them upwardly against the journal for separate frictional contact therewith and with each other, the wheel supporting means comprising a pivot pin in a plane perpendicular to the axis of rotation of the journal, separate, concentric, aligned sleeves encircling and free to rotate through a limited angle about the pin and carrying at their ends opposed overlapping support blocks, bearing pins carried by the blocks on which the wheels are mounted, an elastomeric sleeve interposed between the pin and the aligned sleeves and adhering thereto, the wheels being mounted for rotation on axes located in the vertical plane of the axis of rotation of the journal.

5. A railroad car axle journal lubricator including a yoke structure adapted to encircle the lower portion of a railroad car axle journal including arcuate guide mem-

bers, adapted to extend upwardly around opposite sides of the lower portion of such a journal, a connection between the arcuate members below such a journal, lubricant wheels mounted on such connection for rotation in contact with one another and with such a journal at their peripheries, holding springs extending upwardly along the arcuate guide members adapted to bias the wheels against such a journal.

6. A railroad car axle journal lubricator including a yoke structure adapted to encircle the lower portion of a railroad car axle journal including arcuate guide members, adapted to extend upwardly around opposite sides of the lower portion of such a journal, a connection between the arcuate members below such a journal, lubricant wheels mounted on such connection for rotation in contact with one another and with such a journal at their peripheries, holding springs extending upwardly along the arcuate guide members adapted to bias the wheels against such a journal.

7. A railroad car axle journal lubricator including a yoke structure adapted to encircle the lower portion of a railroad car axle journal including arcuate guide members, adapted to extend upwardly around opposite sides of the lower portion of such a journal, a connection between the arcuate members below such a journal, lubricant wheels mounted on such connection for rotation in contact with one another and with such a journal at their peripheries, holding springs extending upwardly along the arcuate guide members adapted to bias the wheels against such a journal, the arcuate guide members being interposed between the springs and such a journal.

8. A railroad car axle journal lubricator including a yoke structure adapted to encircle the lower portion of a railroad car axle journal including arcuate guide members, adapted to extend upwardly around opposite sides of the lower portion of such a journal, a connection between the arcuate members below such journal, lubricant wheels mounted on such connection for rotation in contact with one another and with such a journal at their peripheries, holding springs extending upwardly along the arcuate guide members adapted to bias the wheels against such a journal, the arcuate guide members being interposed between the springs and such a journal, positioning pads extending laterally from the guide members for contact with such a journal, the pads being parallel with such a journal axis.

9. A railroad car axle journal lubricator, a central tie pin, a pair of sleeves mounted for rotation thereon, overlapping supporting blocks extending from and occupying less than half the circumference of each sleeve, a stub shaft projecting radially from each block, lubricant wheels rotatably mounted on such shafts and means for biasing the pin toward a railroad car axle journal to cause frictional contact of the wheels with one another and with the journal.

10. A railroad car axle journal lubricator, a central tie pin, a pair of sleeves mounted for rotation thereon, overlapping supporting blocks extending from and occupying less than half the circumference of each sleeve, a stub shaft projecting radially from each block, lubricant wheels rotatably mounted on such shafts and means for biasing the pin toward a railroad car axle journal to cause frictional contact of the wheels with one another and with the journal, an elastomeric sleeve interposed between the sleeves and the pin, adhering thereto to flexibly resist while permitting relatively angular movement of the sleeves.

11. A railroad car axle journal lubricator, a central tie pin, a pair of sleeves mounted for rotation thereon, overlapping supporting blocks extending from and occupying less than half the circumference of each sleeve, a stub shaft projecting radially from each block, lubricant wheels rotatably mounted on such shafts and means for biasing the pin toward a railroad car axle journal to cause frictional contact of the wheels with one another

and with the journal, an elastomeric sleeve interposed between the sleeves and the pin, adhering to one to flexibly resist while permitting relatively angular movement of the sleeves, the blocks by contact with one another positively limiting angular displacement of the sleeves.

12. A lubricator for railroad car axles and the like including a horizontal shaft, yielding means for biasing it upwardly, separate aligned sleeves mounted for rotation on the shaft, a bearing pin carried by each sleeve, downwardly and outwardly inclined from the sleeve in a plane perpendicular to the axis of the shaft, friction wheels one on each pin, in contact with one another adjacent their lower peripheries.

13. A lubricator for railroad car axle journals comprising two friction wheels mounted for rotation about inclined intersecting axes, means for supporting them below a car axle journal and biasing them upwardly against the journal for separate frictional contact therewith and with each other, the wheel supporting means comprising a pivot pin in a plane perpendicular to the axis of rotation of the journal, separate, concentric, aligned sleeves encircling and free to rotate through a limited angle about the pivot pin, bearing pins extending downwardly and outwardly one from each sleeve, one wheel being mounted on each bearing pin.

14. A lubricator for railroad car axle journals comprising two friction wheels mounted for rotation about inclined intersecting axes, means for supporting them below a car axle journal and biasing them upwardly against the journal for separate frictional contact therewith and

5 10 15 20 25

with each other, the wheel supporting means comprising a pivot pin in a plane perpendicular to the axis of rotation of the journal, separate, concentric, aligned sleeves encircling and free to rotate through a limited angle about the pivot pin, bearing pins extending downwardly and outwardly one from each sleeve, one wheel being mounted on each bearing pin, an elastomeric sleeve interposed between the pivot pin and the aligned sleeves.

15. A lubricator for railroad car axle journals comprising two friction wheels mounted for rotation about inclined intersecting axes, means for supporting them below a car axle journal and biasing them upwardly against the journal for separate frictional contact therewith and with each other, the wheel supporting means comprising a pivot pin in a plane perpendicular to the axis of rotation of the journal, separate, concentric, aligned sleeves encircling and free to rotate through a limited angle about the pivot pin, bearing pins extending downwardly and outwardly one from each sleeve, one wheel being mounted on each bearing pin, the wheels being mounted for rotation on axes located in the vertical plane of the axis of rotation of the journal.
